DESIGN FOR A CORNER TRIMMING UNIT

Theodore Christie, Rochester, N. Y.

Application August 21, 1937, Serial No. 71,222

Term of patent 14 years

To all whom it may concern:

Be it known that I, Theodore Christie, a citizen of the United States, residing at Rochester, in the county of Monroe, and State of New York, have invented a new, original, and ornamental Design for a Corner Trimming Unit, of which the following is a specification, reference being had to the accompanying drawing, forming a part thereof.

I claim:

The ornamental design for a corner trimming unit as shown.

THEODORE CHRISTIE.
